John H. Sawyer, Attorney.

UNITED STATES PATENT OFFICE.

WILLIAM BROWN, OF SAN FRANCISCO, CALIFORNIA.

HANDLE FOR AIR-BRAKE VALVES.

1,257,799.

Specification of Letters Patent. Patented Feb. 26, 1918.

Application filed August 16, 1917. Serial No. 186,578.

To all whom it may concern:

Be it known that I, WILLIAM BROWN, a citizen of the United States, residing at San Francisco, in the county of San Francisco and State of California, have invented certain new and useful Improvements in Handles for Air-Brake Valves, of which the following is a specification.

This invention relates to an improved air 10 brake valve handle particularly designed for use upon street cars and has as its primary object to provide a handle which may be clamped upon the valve stem so that the said handle cannot become accidentally displaced 15 when manipulating the valve.

The invention has as a further object to provide a handle which may be readily applied to substantially any conventional type 20 of air brake valve as commonly employed upon street cars.

And the invention has as a still further object to provide a handle wherein the grip thereof may be adjusted for clamping the handle upon a valve stem.

25 Other and incidental objects will appear as the description proceeds and in the drawings wherein I have illustrated the preferred embodiment of the invention and wherein similar reference characters designate corresponding parts throughout the several views:

Figure 1 is a side elevation showing my improved handle applied to a conventional type of air brake valve stem,

35 Fig. 2 is a longitudinal sectional view more particularly illustrating the details of the construction of the handle,

Fig. 3 is a vertical sectional view taken on the line 3—3 of Fig. 1 and looking in the 40 direction of the arrows, this view particularly showing the sectional formation of the stop arm of the handle, and

Fig. 4 is a transverse sectional view taken on the line 4—4 of Fig. 2 and looking in 45 the direction of the arrows.

In carrying out the invention, my improved handle is formed with a head 10 provided with a squared socket 11 for receiving the stem of an air brake valve there- 50 through, as illustrated in Fig. 1. In this figure such a valve stem has been conventionally shown at 12. The head 10 is split longitudinally and extending from the extremities thereof are the complemental sec- 55 tions of a shank 13 extending laterally from the head. The shank 13 is split longitudi-

nally throughout the major portion of its length to provide the said shank sections which are formed integrally at the outer end of the shank and are thus connected by 60 a web 14 at the adjacent terminal of the shank. Adjacent their inner extremities, the said shank sections are bowed laterally away from each other and are formed with enlarged portions 15. Rising from the enlarged portions of the shank sections are the complemental sections of a stop arm 16. At their upper extremities, the sections of this arm each carry one section of a laterally directed lug 17 projecting forwardly from the 70 said arm. The arm 16 and lug 17 are arranged to coöperate in the well known manner with the usual stop flange upon the casting of the brake valve to prevent the removal of the handle from the stem 12 except 75 in the neutral position of the valve.

Removably fitting over the outer extremity of the shank 13 is a hollow cylindrical grip 18 provided interiorly with an internally threaded ring 19. The outer extremity 80 of the shank 13 is threaded to coact with this ring so that the grip is thus adjustable upon the shank.

As will now be seen, the grip 18 may be adjusted outwardly upon the shank 13 when 85 the bowed portions of the sections of the said shank will spring apart to spread the head 10 so that the said head may thus be easily fitted upon or removed from the valve stem 12. On the other hand, by adjusting 90 the grip inwardly upon the shank, the bowed portions of the sections thereof will be compressed to consequently compress the head and securely grip the said head about the valve stem. Accidental displacement of the 95 handle when manipulating the valve may thus be positively prevented.

It will therefore be seen that I provide a particularly simple and efficient construction for the purpose set forth and while I 100 have indicated that the improved handle is particularly designed for use upon the air brake valves of street cars still, I do not wish to be limited in this regard as it will be seen that the handle may be employed upon 105 air brake valves in various other situations.

Having thus described the invention, what is claimed as new is:

1. A brake valve handle including a split head, a sectional shank having the sections 110 thereof extending from the extremities of the said head and yieldably connected by

the head, and means adjustable upon the said shank to coact with the sections thereof for clamping the head about a valve stem.

2. A brake valve handle including a split head, a sectional shank having the sections thereof extending from the extremities of the said head and yieldably connected by the head, and a grip adjustable upon the said shank to coact with the sections thereof for clamping the head about a valve stem.

3. A brake valve handle including a split head, a sectional shank having the sections thereof extending from the extremities of the said head and integrally joined at their inner extremities by the head, the said shank sections being integrally formed at the outer end of the shank for connecting the said shank sections at their outer ends, and means adjustable upon the said shank to coact with the sections thereof for clamping the head about a valve stem.

4. A brake valve handle including a split head, a sectional shank having the sections thereof extending from the extremities of the head, the said shank sections being longitudinally bowed away from each other for yieldably spreading the ends of the head,

and a grip adjustable upon the shank for compressing the bowed portions of the said shank sections and clamping the head about a valve stem.

5. A brake valve handle including a split head, a sectional shank having the sections thereof extending from the extremities of the head, the said shank sections being longitudinally bowed away from each other for yieldably spreading the ends of the head, and means adjustable upon the shank for compressing the bowed portions of the said shank sections and clamping the head about a valve stem.

6. A brake valve handle including a head, a shank extending therefrom, the said shank being split longitudinally from a point adjacent its outer end through its inner end to provide coacting shank sections and the head being split between the inner ends of the said shank sections and yieldably connecting the adjacent extremities thereof, and means adjustable upon the shank to coact with the said shank sections for clamping the head about a valve stem.

In testimony whereof I affix my signature.
WILLIAM BROWN. [L. S.]
